UNITED STATES PATENT OFFICE.

ALBERT B. STREETER, OF NEW YORK, N. Y., ASSIGNOR TO DUAL MOTORS CORPORATION, OF NEW YORK, N. Y., A CORPORATION OF DELAWARE.

FUEL INTAKE FOR TWO-CYCLE ENGINES.

Application filed March 7, 1925. Serial No. 13,671.

The invention relates in general to an internal combustion engine of the type in which the smaller end of a differential piston moves in an explosion chamber and the larger end moves in a pump chamber, and in which air under pressure either from the pump chamber associated therewith, or from the pump chamber of a companion unit, is discharged into the explosion chamber, for scavenging the same of its refuse gas and the invention relates specifically to an improved form of two cycle engine.

The present disclosure more particularly relates to the fuel line, or more properly to a high pressure air line, constituting part of the fuel feeding apparatus leading to the explosion chamber. The present disclosure may be considered as one unit of a two-cylinder engine of the type outlined, in which the high pressure air from the pump of one unit is supplied to the explosion chamber of the other unit and otherwise this application may be regarded as a companion case with my co-pending application entitled "Air compressor for internal combustion engines" Serial No. 12,990 filed March 3, 1925.

In two-cycle engines of the type herein disclosed it is a usual practice to inject into the explosion chamber gaseous fuel from a carburetor and to introduce this gaseous fuel at the forward end of the space in the cylinder traversed by the piston on its compression stroke. Instead of using gaseous fuel it is proposed in the present instance to inject into the chamber a charge of liquid fuel in a finely divided state, and to propel the same by a charge of combustion supporting air, all as is more definitely described in my co-pending application Serial No. 642,465, filed May 31, 1923, entitled "Fuel metering valve."

In general the present disclosure features a greater efficiency in utilizing the charge of such finely divided liquid particles than is possible where the charge is fed through the head of the combustion chamber as is disclosed in the said pending application.

This phase of the invention is attained by positioning the combined fuel and combustion supporting air intake port in the side of the cylinder and in spaced relation to the opposite ends of the path of travel of the end of the piston travelling in the explosion chamber.

Another object of the invention is to provide for a cooling of the fuel intake port to avoid detonation or premature explosion at this point and for the fuel metering valve associated therewith, and incidentally to relieve this valve from high back pressures and from the high temperatured heat generated in the chamber during the initial periods of the combustion. At the same time the invention features the utilization of the hot water in the water jacket for the purpose of preheating, at least to same extent, of the fuel particles as they are ejected into the explosion chamber.

Another object of the invention is to provide for a timed control of the high-pressure, combustion-supporting air fed to the metering valve and to produce the same economically and momentarily at the instant when it is needed. Accordingly the present disclosure features the avoidance of this high pressure air on the line except when actually needed.

Various other objects and advantages of the invention will be in part obvious from an inspection of the accompanying drawings and in part will be more fully set forth in the following particular description of one form of device embodying my invention, and the invention also consists in certain new and novel features of construction and combination of parts hereinafter set forth and claimed.

In the accompanying drawings:—

The figure is a view in vertical axial section of an engine cylinder unit disclosing one of the duplicated units of a preferred embodiment of the invention.

In the following description and in the claims, parts will be identified by specific names for convenience of expression but they are intended to be as generic in their application to similar parts as the art will permit.

In the drawing there is shown an engine casing 10 which is preferably one of the pair of cylinder structures shown in the companion application as the units are identical the detailed description of one will be equally applicable to the other. The upper portion of the cylinder is of relatively small internal diameter and forms an explosion chamber 11. The lower part of this cylinder is of greater diameter than the diameter of the explosion chamber and forms a pump chamber 12. There is disclosed a differential area

piston 13, with its small head 14 working in the explosion chamber and with its large head 15 working in the pump cylinder to form an air compressor. The upper end of 5 the explosion chamber is closed by a head 16, positioned centrally in which is a spark plug 17. This head as well as the wall forming the cylindrical part of the explosion chamber is water-jacketed for the entire length of 10 the piston displacement in the explosion chamber except for the ports hereinafter described. This water jacketing will have the usual effect of keeping the explosion engine cool but the metering valve and fuel inlet 15 tube hereinafter described will be heated sufficiently during the operation of the engine to materially raise the temperature of the liquid fuel ejected into the chamber. The illustrated structure will thus tend to 20 preheat the liquid particles at the instant they are blown into the explosion chamber.

At the forward or lower end of the cylinder 11 the wall thereof is provided with a series of exhaust ports 18, circumferentially 25 spaced about one side of the cylinder. Opposite the exhaust ports are a similar line of air scavenging inlet ports 19, supplied with relatively low pressure air from a reservoir 20, in turn supplied from the pump cylinder 12 while acting as a low-pressure air 30 condenser in a manner more particularly described in the companion application.

The advanced end 23 of the piston in its movement towards the closed end or head 16 35 of the cylinder travels from a point slightly below its position uncovering the ports 18 and 19 to a point indicated approximately by the line 21, in spaced relation to the underside of the head to form a shallow explosion space or clearance 22 between the advanced end of the piston and the underside of the closed head 16.

A combined fuel and air inlet port 24 opens into the explosion chamber at a point 40 intermediate the length of the movement of the piston end 23. In a preferred physical embodiment of the invention this fuel port is disposed at a point spaced from the closed head about two and one-half times the mean 45 depth of the explosion space 22. Differently defined this inlet port is located at the point reached by the advanced end 23 of the piston when it has travelled about two-thirds of its compression stroke. This port 50 is formed at the inner end of a bore 25 centered in a tube 26 which extends across the hot water space 27 between the water-jacket 55 forming walls of the cylinder 11.

The fuel leading to the bore 25 is controlled 60 by a fuel metering device 28, contained in a valve casing 29, preferably formed as a casting integral with the side of the cylinder 11. The casing is provided with vertically extending air conduits 30, 65 open at top and bottom and designed to as-

sist in keeping the valve casing cool. The fuel metering device includes a rotary valve 31 of the cylinder type, and is provided with a measuring pocket 32 extending diametrically therethrough. 70

In the case of the dual cylinder construction the rod forming the valve 31 also forms the valve for the companion cylinder and is provided with a measuring pocket corresponding to the pocket 32 herein illustrated. 75

The casing 29 is provided with four ports, which considered clockwise form in order a compressed air inlet 33, a fuel inlet port 34, a discharge port 35, leading into the bore 25 and a bleeding port 36 opening into the 80 external atmosphere. A spray valve 37 controls the passage of fuel through the port 34 and otherwise it is understood that this metering device corresponds in general to the disclosure in my Patent No. 1,609,386, 85 Dec. 7, 1926.

Air under high pressure is supplied to the inlet 33 through a pipe 38 leading from the upper end of the pump chamber 12. Air is required at the metering valve only at the 90 instant when the measuring pocket 32 is in line connecting the bore 25 with the air inlet 33. While an air pressure is needed at this time it is required only for this instant that the air be under extremely high pressure 95 so as to blast the liquid particles through the port 24 into the combustion cylinder. The present disclosure therefore features an arrangement by means of which the supply of air is cut off between the pump cylinder and the pipe 38 until the large head 15 of the piston is moving into its final air 100 compressing position. Preferably the pipe 38 leads to a manifold 46 to which also leads the pipe indicated diagrammatically at 47 105 corresponding to the pipe 38 from the pump of the other cylinder unit. The manifold opens to the inlets 33 of both metering devices, so that there is a blast of air into the manifold as the pistons successively reach the 110 ends of their air compression strokes. The two metering valve are so timed in their rotation that one is opened to admit the air from the manifold as the piston in the other 115 compressor reaches the limit of its compression stroke.

In order to close the pipe 38 from the associated air compressor a valve 39 is positioned in this air line as close as possible to the air compressor. For this purpose there 120 is disposed to one side of the upper portion of the pump cylinder and beneath the reservoir 20 a rotary valve casing 40 in which is mounted a long cylindrical form of rotary valve rod, a portion of which is provided 125 with a diametrically extending passageway to form the valve 39. Portions of this valve rod are utilized to control the low pressure air from the pump cylinder into the reservoir, as more particularly described in my 130

companion application. The diametrically extending passageway 41 places in communication diametrically disposed passageways or ports 42 and 43 extending horizontally through opposite sides of the valve casing 40. Passageway 42 communicates with pipe 38 and passageway 43 extends through the adjacent wall at the upper portion of the pump cylinder 12. The upper portion of the wall of the pump cylinder from the entrance of the passageway 43 to the shoulder 44 which limits the travel of the piston head 15 on its compression stroke, is slightly recessed longitudinally to provide a by-passageway 45 around the advanced edge of the head 15. From this construction it will be seen that even after the piston head 15 passes the inner end of the passageway 43, the air compressor is open to the valve 39 to the limit of the piston movement. At the instant the air compressor is exerting maximum pressure on the contained air, this air is open to the valve so that when the valve is rotated into position to open the air supply to the pipe 38 a source of high pressure air is immediately available to the associated or the other explosion chamber.

A hot target or baffle extends upwardly from the end 23 of the piston and is disposed to be moved with the piston into the path of the charge of incoming full particles to assist in vaporizing the same and to turn the stream towards and into the combustion space 22.

In operation it will be apparent that as the small piston end 14 moves upward towards the fuel inlet port it will be compressing pure fresh air taken in through the ports 19. Incidentally during this initial movement of the piston the large end 15 of the piston will be supplying low pressure air to the scavenging air reservoir 20, as more particularly defined in the companion application.

As the piston advances from its position closing the scavenging and exhaust ports it acts to compress the air trapped in the explosion chamber. During this time the metering valve 31 is turning towards and past its position receiving its charge of finely divided liquid fuel and moving the same towards its position aligned with the high pressure air inlet 33. Just prior to the time the upper end of the piston reaches the fuel port 24 the metering valve has reached the horizontal position in which the same is opened to the explosion chamber. At this instant the air valve of the other unit and corresponding to the valve 39 controlling the high pressure air line is opened and a blast of air under the maximum available pressure is directed through the metering valve to project the liquid particles into the combustion chamber. By this time the baffle projecting upwardly from the hot end of

the piston has advanced into the path of the fuel charge and this hot baffle reacts on the preheated fuel to assist in vaporizing the same. The baffle acts as a hot spot or target against which is projected the fuel. The baffle is so disposed that it acts additionally to turn the path of the fuel stream upwardly towards the closed end of the cylinder, thus projecting a rich mixture of fuel and air into the explosion space 22 where it can be fired by the spark plug on the advance of the piston into its proper firing location.

As the piston moves past the fuel inlet valve on the compression stroke it will, of course, close this port but this closing is immaterial for by this time the metering valve has rotated into position to shut off the supply of fuel and air. Just prior to the instant of maximum compression the charge is fired, the piston moves on its working stroke and at the end of the stroke uncovers the air scavenging and exhaust ports, thus permitting the cylinder to be scavenged of its refuse gas as is well known in this art. The cycle of operation is thus repeated, each explosion chamber alternately receiving and firing its contained charge.

By means of a device of this character it is possible to obtain a higher efficiency than has been possible heretofore in engines of this type.

The construction disclosed features a relatively cool engine and apparently the locating of the fuel metering valve away from the hot head facilitates accuracy in the control of the liquid fuel in such a way as would not be possible with the fuel if it were in its usual gaseous condition. A greater efficiency in operation has been attained by placing the fuel intake in the side than was obtained when it was disposed in the head at the place now occupied by the spark plug.

The present disclosure provides a fuel feeding system which utilizes high pressure air and yet does not require expensive forms of packing and valves for holding the pressure. This is apparently due to the fact that the high pressure is not retained, but is used as soon as generated. The use of two valves tends to minimize leakage and insures the momentary holding of the high pressure until the air line is open to the explosion chamber. It is within the scope of the disclosure where only one cylinder unit is desired, to have the metering valve supplied with high pressure air from the compressor positioned below the same as disclosed in the drawings, making the necessary changes in the periodicity of the valves 31 and 39 or utilizing the pipe 38 as a small reservoir.

While I have shown and described, and have pointed out in the annexed claims, certain novel features of my invention, it will be understood that various omissions, sub-

stitutions and changes in the form and details of the device illustrated and in its operation may be made by those skilled in the art without departing from the spirit of the invention.

Having thus described my invention, I claim:—

In an internal combustion engine, the combination of an explosion chamber and a pump chamber, a differential piston having its smaller head working in the explosion chamber and its larger head working in the pump chamber, said combustion chamber provided with a fuel inlet port intermediate its length and controlled by the smaller head of the piston, a fuel metering device including a rotary valve for measuring the fuel supplied to said inlet port, means for

supplying fuel to said valve, a high pressure air conduit leading from the pump chamber adjacent its high pressure end to said metering device to blow from the metering device the fuel charge measured by the valve and to eject the same into the explosion chamber, a rotary valve controlling the air flow in said conduit, said rotary valves being operatively connected to operate in timed relation to the piston travel to cause the high pressure air to eject the fuel into the explosion chamber when the fuel inlet port is uncovered.

Signed at New York, in the county of New York and State of New York, this 23rd day of February, A. D. 1925.

ALBERT B. STREETER.
